UNITED STATES PATENT OFFICE.

WILLIAM E. COLLINS, OF HOUSTON, TEXAS.

REGIN FOR COTTON AND OTHER FIBROUS MATERIAL.

1,412,167.

Specification of Letters Patent. Patented Apr. 11, 1922.

Application filed September 9, 1919. Serial No. 322,646.

To all whom it may concern:

Be it known that I, WILLIAM E. COLLINS, citizen of the United States, residing at Houston, in the county of Harris and State 5 of Texas, have invented certain new and useful Improvements in Regin for Cotton and other Fibrous Material, of which the following is a specification.

This invention relates to new and useful 10 improvements in a regin for cotton and other fibrous material.

One object of the invention is to provide a machine of the character described specially adapted for use in reginning and reconditioning cotton. In handling baled cotton as it comes from the gin, and particularly in compressing the same there is a certain amount of waste, and low grade cotton thrown aside as unfit to enter the compressed bale, and it is the object of this invention to provide a machine by means of which this waste and low grade cotton may be re-conditioned and prepared for market and the grade thereof materially improved.

Another object of this invention is to provide a machine of the character described which is of simple construction and which may be cheaply and easily manufactured and readily applied to the ordinary gin now 30 in common use.

With the above and other objects in view the invention has particular relation to certain novel features of construction, operation and arrangement of parts, an example 35 of which is described in this specification and illustrated in the accompanying drawings wherein:

Fig. 1 is a longitudinal sectional view, and

Fig. 2 is an enlarged fragmentary plan 40 view of the gin saws, showing their driving means.

Referring now more particularly to the drawings, wherein like numerals of reference designate similar parts in each of the 45 figures, the numeral 1 designates the casing, or framework, as a whole. Rotatably mounted within this casing are the transverse shafts 2 and 3, which are rotated in the directions indicated by the arrows, in 50 Fig. 1, the former, in practice having a greater speed than the latter. The shaft 3 is driven through the pulley 15, fixed thereon, and is operatively connected with, and drives, the shaft 2, through the large and

small gears 16 and 17, fixed on said respective shafts. Fixed upon these respective shafts are the gin saws 4 and 5, said saws of the respective shafts being spaced apart by means of the circular spacing blocks 6 and 7, forming in effect drums. The saws 60 of the respective shafts overlap and are arranged in staggered relation so that the saws of one shaft will work between those of the other shaft. Underneath these saws there is arranged a travelling endless belt or 65 apron 8, on to which the cotton is fed from the hopper 9 and which delivers the same within range of the feed saws 5 which carry the same up within reach of the saws 4, and these latter, rotating at a rapid rate of speed, 70 catch the fiber and separate the same into a loose and fluffy mass relieving the fiber of lumps and knots and densely compacted masses and rendering the same loose and clean. In front of the saws 6 and above the 75 saws 7 are the respective drum-like rotatable brushes 10 and 11, which rotate in the directions indicated by the arrows in Fig. 1. These brushes are located adjacent the inlet ends of the respective lint flues 12 and 13 80 and generate an air current therethrough and the lint cotton is brushed from the adjacent saws, by said brushes and then carried by the air current through said flues and delivered to the conveyor flue 14 through 85 which it is carried to the condenser (not shown).

What I claim is:—

A device of the character described including a framework, a plurality of transverse rotatable shafts mounted therein, circular saws fixed on each shaft and spaced apart, and revolving in opposite directions, the saws of one shaft being staggered relative to those of the other shaft and working between them, one of said saws revolving at a greater speed than the other, a rotatable cylindrical brush arranged adjacent each set of saws, a lint flue, disposed with its inlet end adjacent each brush and a conveyor 95 flue into which the lint flues discharge.

In testimony whereof I have signed my name to this specification in the presence of two subscribing witnesses.

WILLIAM E. COLLINS.
